UNITED STATES PATENT OFFICE.

WILLIAM H. DE FORD, OF MICHIGAN VALLEY, KANSAS.

INDICATOR.

1,201,943.

Specification of Letters Patent.

Patented Oct. 17, 1916.

Application filed January 11, 1915. Serial No. 1,655.

To all whom it may concern:

Be it known that I, WILLIAM H. DE FORD, a citizen of the United States, residing at Michigan Valley, in the county of Osage 5 and State of Kansas, have invented certain new and useful Improvements in Indicators; and I do hereby declare the following to be a full, clear, and exact description of the invention, such as will enable others 10 skilled in the art to which it appertains to make and use the same.

This invention relates to indicators, and more particularly to that type of indicators especially designed for use in railway cars 15 to indicate streets and stations.

The invention has for its principal object to provide a novel and efficient indicator and an automatic operating means therefor.

Another object is the provision of an indicator embodying a pair of spring actuated spools, on which the indicator cloth is wound and means for controlling the movement of the cloth.

With these and other objects in view, the 25 invention consists in the novel construction, arrangement and formation of parts as will be hereinafter specifically described, claimed and illustrated in the accompanying drawing, in which:

30 Figure 1 represents a front elevation of the indicator. Fig. 2 represents a fragmental rear elevation thereof. Fig. 3 represents a vertical sectional view on the line 3-3 of Fig. 1. Fig. 4 represents a horizontal sectional view on the line 4-4 of Fig. 1. Fig. 5 represents an enlarged detail sectional view on the line 5-5 of Fig. 1. Fig. 6 represents a fragmental front elevation of a railway car and track, illustrating the operating means for the indicator. Fig. 7 represents a fragmental front elevation of a car illustrating the operating means for the indicator associated with the trolley wire supports of an electric railway. 45 Fig. 8 represents an enlarged sectional view, partly broken away, on the line 8-8 of Fig. 5.

Referring to the drawing in detail, the 50 numeral 10 indicates the casing of the indicator, the front wall of which is provided adjacent the top and bottom with semi-cylindrical enlargements 11 in which are rotatably mounted shafts 12. Spools 13 are rotatably mounted upon the shafts 12 and a 55 pair of spaced strips 14 are secured at opposite ends to the spools 13. A plurality of

removable and interchangeable sections or signs 15 are secured to the strips 14 and are adapted to be successively moved behind a glass covered opening 16^a in the front of 60 the casing 10 so as to be visible to the occupants of the car.

Spring casings 16 are secured at the ends of the semicylindrical enlargements 11 and receive the extremities of the upper and 65 lower shafts 12. A shell 17 is secured to one end of each shaft 12 and rotatably receives the inner extremity of a crank shaft 18 having a crank 19 on its outer end. A coil spring 20 is secured at opposite extremities to the shell 17 and the crank shaft 18. A ratchet wheel 21 is secured to the crank shaft 18 intermediate the outer wall of the casing 16 and the spring 20 and cooperates with a pivoted pawl 22 to lock the 70 shaft 18 against rotation in one direction. The end of each shaft 12 opposite its actuating spring 20 slidably receives a relatively 75 non-rotatable clutch member 23 having teeth at its opposite ends adapted to alternatively 80 engage teeth 24 on the adjacent end of the spool 13 and teeth formed in the adjacent portion of the casing 10, whereby the shaft 12 may be locked for rotation with the spool 13 or locked against rotation within the 85 casing 10, when desired. The clutch member 23 is formed centrally with a circumferential channel receiving the diametrically opposed pins carried by the bifurcated inner extremity of a bell crank 25, one end 90 26 of which projects laterally through an aperture in the side wall of the casing 10, whereby the clutch member may be conveniently actuated.

A plurality of laterally projecting lugs or 95 projections 28 are secured to one of the flexible strips 14 and are adapted to be engaged by the rod 29 to stop the movement of the strips 14 under the influence of either of the springs 20 located in the spring casings 16. 100 The inner end of the rod 29 is slidably mounted through an opening 29^a in one of the side walls of the casing 10 and the upper and lower edge portions of the opening are beveled to permit the outer end of the rod to 105 swing vertically. The outer end of the rod 29 is pivotally secured by a pivot pin 29^b to the rear face of a wheel 30 rotatably supported in a laterally projecting plate 31 carried by the casing 10 upon a shaft 32. A 110 spring casing 33 is secured to the front face of the plate 31, and receives the forward ex-

tremity of the shaft 32 and provides a housing for a spring 34 normally tending to rotate the shaft 32. A suitable crank 35 is secured in the front wall of the casing 33, 5 whereby the actuating spring 34 for the shaft 32 may be wound up. The tension of the spring 34 normally tends to rotate the wheel 30 in the direction of the arrow in Fig. 2 at a greater speed than that which the 10 spools 13 are driven by the springs 20 and the wheel 30 is limited in its rotational movement by the locking member 37 pivotally secured between a pair of arms 38 secured to the rear face of the plate 31 and extending 15 behind the wheel 30. The locking member 37 is of angular formation and one end thereof is provided with a forwardly projecting tooth 39 adapted to engage behind the pivoted end of the rod 29 to stop the latter, together with the wheel 30. The locking member 37 is disengaged from the rod 29 by 20 a spring 40 projecting laterally from a slide rod 41 slidably supported behind the plate 31 and normally retained in inwardly extended position by the tension of a spring 42, adapted to engage the end of said member opposite the tooth 39.

The slide rod 41 is operably connected with one crank arm of a shaft 44 rotatably 30 mounted in the upper portion of a railway car 45 and adapted to be oscillated by the engagement of another angularly directed crank arm 46 thereof engaging a trip member 47 suitably supported from a trolley wire 35 support 48 arranged above the car 45. The slide rod 41 is also connected by a bell crank 49 and a link 50 with a bell crank 51 pivotally supported beneath the car 45 and having a depending arm adapted to engage a 40 trip member 52 secured adjacent the rail 53 of the track.

In operation, the spring 20 in one of the casings 16 is wound up and the clutch member 23 associated with the other shaft 12 is 45 moved so as to lock said shaft against rotation within the casing 10 and permit the spool 13 thereon to freely rotate. Presuming that the upper spring is wound and the shaft 12 operated by the lower spring is 50 locked against rotation the upper shaft 12 and spools 13 associated therewith are rotated until one of the lugs or projections 28 on the strip 14 is engaged with the inner end of the rod 29, as illustrated in Fig. 2, 55 and the movement of the indicator is thus stopped. It will be understood that the trip devices 47 and 52 are arranged at points slightly in advance of the stops to be made by the car and when the members 46 and 51 60 engage the trip devices the slide rod 41 is moved longitudinally outwardly of the plate

31. During the outward movement of the rod 41 the spring 40 is flexed by and passes the rear end of the locking member 37, the tooth 39 of which latter bears against the 65 wheel 30. When the members 51 and 46 pass the trip members 52 and 47 respectively, the slide rod 41 is automatically returned to initial position by the tension of the spring 42, the spring 40 engaging the rear extremity of the locking member 37, rocking the latter upon its pivotal axis and swinging the tooth 39 out of the path of the adjacent extremity of the rod 29 thus permitting the wheel 30 to rotate under the influence of the 70 spring 34. The rod 29 being pivotally secured eccentrically of the wheel 30 is moved a distance outwardly and the inner extremity thereof is disengaged from the projection or lug 28, thus permitting the strips 14 and 80 sections 15 to move a distance upwardly under the influence of the spring 20 in the upper casing 16. As the wheel 30 rotates at a greater speed than the spools 13, it is evident that only one lug 28 will pass before the 85 rod 29 is again moved inwardly to its initial operative position. When the wheel 30 completes one revolution the rod 29 is again moved to the position illustrated in Figs. 2 and 5 and the tooth 39 of the locking member 90 36 engages and locks the rod 29 against a subsequent operation. During the travel of the car 45 either or both of the members 46 and 51 are operated by the trolley or track-carried switch members 47 and 52 respectively and the sections 15 are successively moved into view behind the transparent section 16.

What I claim is:

An indicator comprising a casing, spools 100 rotatably mounted in the upper and lower portions of said casing, an indicator strip secured at opposite ends to said spools, springs connected with said spools for rotating the latter to wind said indicator strip 105 thereon, means for disconnecting said springs from said spools, a plurality of projections carried by said indicator strip, a rod slidably mounted through said casing adapted to engage said projections to limit 110 the movement of said strip, spring actuated means normally tending to reciprocate said rod, means to lock said rod against reciprocation, and object engaging means associated with said locking means to release said rod. 115

In testimony whereof I affix my signature in presence of two witnesses.

WILLIAM H. DE FORD.
